UNITED STATES PATENT OFFICE.

ALBERT OLGAY, OF GLEN ELLYN, ILLINOIS, ASSIGNOR TO GAW-O'HARA ENVELOPE COMPANY, OF CHICAGO, ILLINOIS, A CORPORATION OF ILLINOIS.

ENVELOPE-WINDOW-CUTTING DEVICE.

Application filed September 28, 1925. Serial No. 58,967.

This invention relates to a device adapted to cut windows or other openings in envelopes and to an arrangement of such device with a printing press or the like whereby 5 any matter may be printed upon the envelope at the same time and during the same operation of cutting the window or other opening in the envelope. More particularly the invention relates to a knife adapted to be 10 mounted on the usual type plate cylinder of a high speed rotary printing press whereby windows may be cut in envelope blanks during the printing operation.

Heretofore it has been usual to cut windows and the like in envelope blanks by hand or by machine presses carrying one or more knives arranged in the shape of the opening or perforation to be cut in the envelope blank and to thereafter print whatever 20 matter be desired on the blank, or the opposite steps were carried out; i. e., the blanks were first printed and thereafter the opening cut in the manner above set forth. With my invention, however, I have eliminated 25 the two steps heretofore thought necessary and complete both operations at one and the same time.

One of the primary objects of my invention therefore, is to provide a knife or die 30 adapted to cut window openings or other perforations in envelope blanks during the printing operation or simultaneously therewith and to provide a cooperative pad which may be arranged on the platen for cooperation 35 with the printing plate or cylinder.

Many other advantages and novelties of construction and operation should be readily appreciated after reading the following description and claims and after viewing the 40 drawings in which:

Fig. 1 is a side elevation view partly in section of a well known type of printing press adapted to continuously feed and continuously print and continuously eject envelope blanks.

Fig. 2 is an enlarged detail of the type plate cylinder and its operative platen taken on a plane parallel with but to the rear of the gears shown in Fig. 1.

Fig. 3 is a side or front elevation of the type plate cylinder illustrated on the scale of Fig. 2 and

Fig. 4 is a fragmentary section taken on the line 4-4 of Fig. 3.

Referring to the drawings, the printing

press illustrated is mounted upon a base frame 2 carrying any suitable prime mover indicated at 3 driving a suitable transmission indicated at 4, 5 and 6 to drive the platen of the press, the axis of which is indicated at 60 7 and thus the type plate cylinder, the axis of which is indicated at 8 through the intermediary of cooperative gears 9. An envelope blank magazine 11 supplies envelopes indicated at 12 through a feed mechanism 65 including a feed roll indicated at 13 to and between the type plate cylinder and its cooperative platen. After the blank has been printed upon and the opening cut there-through, it passes into an appropriate 70 mechanism indicated at 14 adapted to receive the blanks after the printing and adapted to stack them in alignment or otherwise dispose of them.

The type plate cylinder 15 is of the usual 75 type providing flanged or headed projections 16 with intermediate slots 17 in two directions within which blocks or bolt heads may be adjustably secured for securing both the type plates and the knife plate in place upon the cylinder in any desired relation to one another and to the blanks to be printed. In the present instance, I have shown blocks 18 within the slots 17 for engagement of screws 19 passing through the hold-down blocks 21 for securing the hold-down blocks and thus the knife plate 22 firmly against the surface of the heads 16 of the cylinder face. Preferably the knife plate 22 is provided with beveled edges indicated at 23 and the hold-down blocks 21 are likewise correspondingly beveled to obtain a wedging action against the plate. With the knife plate thus securable to the type plate cylinder, the knife plate may be moved to any position with respect to the type on the plate cylinder in order that the window opening in the envelope may be cut at any desired position with respect to the type, i. e., the opening may be cut at a point centered or offset with 90 respect to the printed matter contained on the envelope, and one of the important objects of my invention is subserved.

The knife plate 22 is formed in the shape of a segment of a cylinder with its back 105 face, i. e., the first to be disposed against the curved contour of the cylinder, curved to correspond with the cylinder of the cylinder press. In other words, the rear face of the knife plate or body portion of the knife 110

is of generally rectangular shape and curved only in the direction of its minor axis being straight in the direction of its major axis. Likewise the knife blade, the edge of which is indicated at 24, has said edge lying in a surface in space concentric with the surface of the cylinder.

The platen cylinder 25, of any usual or preferred construction, is in the present instance, provided with one or more longitudinal bars 26 inset below the cylindrical surface to provide anchors for one or more paper blankets 27 covering the surface of the platen cooperative with the type and cutter holding surfaces of the type plate cylinder. The opposite ends of the sheets of paper or paper blankets 26 are suitably anchored as at 28 or in any other desired manner and preferably between these blankets or sheets of paper, a thin metal pad 29 is placed in a position where it will cooperate with the blade of the knife carried on the type plate cylinder. This metal pad 29 is preferably of relatively soft metal compared to the metal of the knife blade in order that it may not dull the edge of the knife. The sheet of paper or the paper blanket 26 may be loosely secured over the face of the pad which is preferably glued or otherwise fixed to the inner sheet or it may be glued or otherwise secured thereto in the same manner as the plate is secured to the inner sheet.

For a purpose well known and well understood but to which general reference will be made, bearers 31 and 32 are cooperatively arranged at or adjacent the ends of the type plate cylinder and the platen cylinder, in order that they compensate for the depth of rise of the type and knife bodies above the surface of the type plate cylinder, and both cylinders are arranged in full floating bearings of any well known or preferred construction.

In operation the envelope blanks are fed between the type plate cylinder and the platen in predetermined timed relation and on their passage between these cylinders they are printed in the desired places and provided with an opening at one and the same operation. From this point the sheets may be stacked by any suitable mechanism or otherwise disposed of as desired. The knife edge may be maintained sharp in any suitable manner, care being exercised to keep all points of its edge in the same cylindrical surface in space concentric with the cylinder.

drical surface of the cylinder and from time to time the pad 29 may be renewed as after several hundred thousand blanks have been cut, an objectionable groove will be formed therein.

Many changes may be made in the construction and operation involving wide departure from the form of the invention shown and described without departing from the spirit of the invention as will be obvious. For this reason, I desire to be limited only by the spirit of the invention and the scope of the appended claims.

I claim:

1. The combination with a printing press adapted to print on envelope blanks, of means relatively adjustable with respect to the print type for cutting a window in each envelope.

2. The combination with a printing press having a type plate and a cooperative platen constructed and arranged for printing envelopes, of means adjustably associated with said plate and cooperative with said platen for cutting a window in each envelope.

3. The combination with a printing press having a type plate cylinder, a cooperative platen and means for successively feeding individual sheets of material between said cylinder and platen for printing thereon, of a knife on said cylinder constructed and arranged for adjustment thereon with respect to the type, and a metal pad on said platen for cooperation with said knife for cutting a perforation in each sheet of material fed therebetween simultaneously with printing upon the sheet.

4. The combination with a printing press having a plate cylinder and a cooperative platen, of means for cutting a perforation in material blanks fed between said cylinder and platen comprising, a knife adjustably secured to the face of said cylinder and a metal pad cooperative with said knife secured on said platen.

5. The combination with a printing press having a type plate cylinder and a cooperative platen cylinder having cooperative bearers, of a knife of generally rectangular cutting edge secured on the plate cylinder and constructed and arranged for adjustment with respect to type on said plate cylinder and a pad for said knife secured on said platen cylinder.

In witness of the foregoing I affix my signature.

ALBERT OLGAY.
